MERCHANDISING DISPLAY STAND

Billie Swan Brown, 4339 Jett Road NW. 30327, and
Martha Lynn Bennett, 261 Colonial Homes Drive NW.
30309, both of Atlanta, Ga.

Filed June 26, 1974, Ser. No. 483,214

Term of patent 14 years

Int. Cl. D20—02

U.S. Cl. D6—158

FIG. 1

FIG. 3FIG. 4*FIG. 5*FIG. 6

FIG. 1 is a perspective view of a merchandising display stand embodying our new design;

FIG. 2 is a top plan view thereof;

FIG. 3 is a front elevational view;

FIG. 4 is a left end elevational view of the merchandising display stand shown in FIG. 1;

FIG. 5 is a rear elevational view thereof; and

FIG. 6 is a right end elevational view of the merchandising display stand shown in FIG. 1.

We claim:

The ornamental design for a merchandising display stand, as shown and described..
